SHROUD FOR A HAY BALER

James R. McGirk, Medinah, Ill., and William D. Syrett,
South Bend, Ind., assignors to International Harvester
Company, Chicago, Ill., a corporation of New Jersey

Filed Oct. 15, 1962, Ser. No. 72,098

Term of patent 14 years

(Cl. D40—1)

Fig. 1.

Fig. 2.

FIG. 1 is a perspective view illustrating the rear and one side of a shroud for a hay baler embodying our new design;

FIG. 2 is a perspective view showing the front and opposite side thereof;

FIG. 3 is a top plan view of the shroud.

The portions of a hay baler shown in broken lines are included for illustrative purpose only.

We claim:

The ornamental design for a shroud for a hay baler, as shown and described.
